ABSTRACT: Members of generally boomerang shape but having outwardly extending hooks are adapted to be thrown by players at a spaced fixed target whereby, if properly aimed and thrown, the member will hook onto the target. The target includes a plurality of vertically extending lengths of rope supporting a plurality of vertically spaced balls.

PATENTED JUL 27 1971

FIG. 1

FIG. 2

FIG. 3

INVENTOR
MICHAEL J. BURCENSKI

**BOOMERANG SHAPED PROJECTILE AND ROPE
TARGET THEREFOR**

SUMMARY OF THE INVENTION

In my invention, throwing members are each formed from a boomerang having three outwardly extending coplanar hooks, one hook being disposed at each end, and the remaining hook extending outward from the convex curved edge in the region of the midpoint. My target comprises a plurality of spaced parallel vertical lengths of rope or the like carrying vertically spaced balls or the like and held in position by suitable supporting means.

The players take turns throwing the members from a selected distance at the target. A member properly aimed and thrown will be so oriented, when arriving at the target, that a hook thereof will engage a length and will slide down until it contacts a ball whereby it is held in place, i.e., is hooked to the target.

BRIEF DESCRIPTION OF THE DRAWINGS

In the drawings:

- FIG. 1 is a perspective view of my invention in use;
- FIG. 2 is a detail view of my throwing member; and
- FIG. 3 is a detail view of my target with my member hooked thereon.

**DETAILED DESCRIPTION OF PREFERRED
EMBODIMENTS**

Referring now to FIGS. 1-3, a flat curved boomerang 10 having an outer convex curved edge 12 is provided at each

end with a separate outwardly extending coplanar curved hook 14 and is provided with an additional like coplanar hook extending outward from edge 12 adjacent the midpoint thereof.

5 My target comprises a vertical post 16 having a bottom pointed end 18 which can be forced into the ground. Two or more horizontally extending members 20 intersecting at their midpoints to the top end of the post. A vertical length of flexible rope 22 or the like is associated with each end of each member 20, being secured thereto and hanging downward therefrom. A plurality of vertically spaced balls 24 are secured to each rope, for example, by having axial bores through which the rope can extend.

15 When my throwing member is properly aimed and thrown at the target, for example at a distance of 40 feet, it can hook itself thereon.

While I have described my invention with particular reference to the drawings, such is not to be considered as limiting its actual scope.

I claim:

1. A game comprising:
- a. a target;
- b. said target including means supporting a plurality of spaced, parallel, vertically extending lengths of rope,
- c. each of said ropes supporting a plurality of vertically spaced balls;
- d. a throwing member,
- e. said throwing member being a flat, boomerang-shaped element with a convex, curved outer edge and three hooks secured to said element, in a coplanar relationship, integral therewith, and extending therefrom.
